UNITED STATES PATENT OFFICE.

HARRY G. KNAPP AND WILLIAM G. HANCOCK, MINOT, NORTH DAKOTA.

CLOSURE-OPERATING MECHANISM.

Application filed June 3, 1924. Serial No. 717,593.

To all whom it may concern:

Be it known that we, HARRY G. KNAPP and WILLIAM G. HANCOCK, citizens of the United States, residing at Minot, in the county of Ward and State of North Dakota, have invented certain new and useful Improvements in Closure-Operating Mechanisms, of which the following is a specification, reference being had to the accompanying drawings.

This invention relates to certain improvements in closure operating mechanisms and it is an object of the invention to provide a novel and improved mechanism of this general character particularly designed and adapted for use in connection with doors of either a swinging or sliding type.

It is also an object of the invention to provide a novel and improved mechanism of this character for use in connection with a door or doors associated with a driveway and wherein the mechanism is so mounted or arranged to offer no hinderance or obstruction to the free passage of a vehicle when said door or doors may be in open position.

Furthermore it is an object of the invention to provide a novel and improved mechanism of this general character wherein either mechanical or manual means may be employed to effect the desired opening or closing of the door or doors, the manual means being preferably for use in emergency such as when the mechanical means may be ineffective.

Another object of the invention is to provide a novel and improved mechanism of this general type operating to effect an opening or closing of a door or doors together with a shock absorbing medium functioning at a time before the door is completely opened or closed, said absorbing means also operating to effect the complete opening or closing of the door.

An additional object of the invention is to provide a novel and improved mechanism of this general character wherein a flexible medium such as a cable is operatively engaged with a door to be opened or closed together with means to impose requisite pull upon said flexible means or cable to effect the desired opening or closing movement.

A still further object of the invention is to provide a novel and improved mechanism of this general character constructed and operating in a manner to prevent injury to a

person who may be caught by a door when closing.

A further object of the invention is to provide a novel and improved mechanism of this general character which may be mounted or arranged within the building with which the doors are associated and constructed in a manner whereby a single endless cable may be employed to transmit the requisite power to open and close the doors.

The invention consists in the details of construction and in the combination and arrangement of the several parts of our improved closure operating mechanism whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a view in top plan illustrating a mechanism constructed in accordance with an embodiment of our invention in applied position, the second position of the doors being indicated by broken lines;

Figure 2 is an enlarged fragmentary view partly in elevation and partly in section of the means for rotating the drum as herein disclosed;

Figure 3 is a view in top plan of the structure as illustrated in Figure 2;

Figure 4 is a sectional view taken substantially on the line 4—4 of Figure 2;

Figure 5 is a fragmentary elevational view illustrating the operating crank in applied position;

Figure 6 is a view of the crank unapplied;

Figure 7 is a fragmentary elevational view illustrating the doors in closed position and the relation of the parts of the mechanism thereto;

Figure 8 is a fragmentary view in top plan illustrating the doors in open position;

Figure 9 is a fragmentary view in top plan, illustrating a further embodiment of our invention;

Figure 10 is a fragmentary elevational view of the structure as illustrated in Figure 9;

Figure 11 is a view in perspective of the

meeting ends of the doors in closed relation; and

Figure 12 is a fragmentary view in perspective of the meeting ends of the doors separated.

In the embodiment of the invention as illustrated in Figures 1 to 8, our improved mechanism is particularly adapted for use in connection with doors of a swinging type and wherein a pair of doors D are supported for swinging movement and moving outwardly into open position.

The upper portion of each of the doors D adjacent its inner or hinged marginal portion is provided with an inwardly disposed plate 1. This plate 1 is in the form of a right triangle. Supported within the building at a predetermined point inwardly of the door opening at one side thereof is a double sheave 2 and carried by the door casement adjacent to the outer ends of the plates 1, when the doors are closed, are the double sheaves 3 and 4. Supported by the wall at the opposite side of the door opening and inwardly thereof is a single sheave 5. A cable 6 passes around the single sheave 5 while the stretches a and b of said cable are operatively engaged with the sheaves 2, 3 and 4, said stretches being connected, as at 7, with the outer end portions of the plates 1 so that upon pull being imposed upon one of the stretches the doors D will be swung outwardly in unison into open position while pull upon the second stretch will swing said doors inwardly into closed position.

The cable 6 is of an endless type and is wrapped around a drum 8 and suitably secured or attached, as at 9, at a point arranged substantially at the transverse center of the periphery of said drum or more particularly the peripheral groove 10 in which the cable is wrapped. The cable may be wrapped around the drum any desired number of times but preferably three.

As herein disclosed, the drum has formed with a side face thereof a gear 11 concentric to the axis of the drum and disposed axially through the drum 8 and gear 11 is an opening 12 through which is adapted to be disposed a supporting axle 14. The portion 14^a of the axle 14 inwardly of the drum 8 is enlarged to provide a head which snugly fits within an opening 15 provided in a supporting member 16 such as a plank of requisite dimensions. The outer portion of the head is defined by an outstanding flange 17 which contacts with the inner face of the supporting member 16 and disposed through said flange 17 and supporting member 16 are the bolts 18. This particular mounting of the axle 14 assures requisite strength to offset the strain imposed thereupon when the drum 8 is rotated to move the doors into either open or closed

position or to which said axle may otherwise be subjected.

While the drum 8 may be rotated in either direction as required by any desired means we prefer to employ the arrangement illustrated in the accompanying drawings wherein the gear 11 has in mesh therewith from above a rack 19 of requisite length and which is detachably connected by a bolt 20 or the like with the outer end portion of the rod 21. Carried by the opposite end portion of the rod 21 is the piston 22 having rectilinear movement within the cylinder 23 suitably mounted upon the support 16 hereinbefore referred to. In communication with the cylinder 23 at opposite sides of the piston 22 and preferably through the heads 24 are the pipe lines 25 leading from a suitable source of air under pressure, the flow through said lines being controlled in any desired manner as by a suitable valve or valves (not shown).

Upon air under pressure being admitted within the cylinder through one end thereof the rack 19 will be operated in a direction to move the doors D into open position while admission of air under pressure at the opposite side of the piston 22 will serve to move the doors D into closed position.

Threaded through the outer head 24 of the cylinder 23 is a bolt 26 which serves as a stop to limit the movement of the piston 22 in one direction. By adjusting or varying the position of this bolt 26 the stroke of the piston 22 may be regulated to compensate for doors of varying widths and which is of especial advantage when the doors are of a sliding type as will hereinafter be more particularly referred to.

Adjacent to the double sheave 2 is an outstanding bracket or arm 27 to which are secured the retractile members or coil springs 28 and 29 coacting respectively with the stretches a and b of the flexible member or cable 6, each of said members or springs being provided at its outer ends with the rollers 30 engaging with the stretch a or b. By this arrangement the springs or members 28 and 29 serve to maintain the stretches a and b of the cable 6 taut and in a manner whereby when the doors D are in closed position one of said members or springs, as 28, is under tension.

In practice, the piston 22 goes to the end of its stroke before the doors are fully closed or fully opened and at which time one of the springs, as 28, is fully extended. The action of this extended spring is to equalize with the second spring 29 which, together with the momentum of the doors D, serve to bring the doors together or into complete closed position. The member or spring 29 being substantially fully contracted when the stroke of the piston 22 is ended serves to retard the momentum of the doors D and

thereby permits them to come together easily and without danger. In other words these springs 28 and 29 serve as a shock absorbing medium and without which the doors would 5 soon pound themselves to pieces. This shock absorbing medium as afforded by the springs 28 and 29 also serves as a safety device for the reason that the action of the piston 22 ceases before the doors are fully closed and 10 this permits a person or more particularly an arm or leg to be caught between the doors without serious injury as there would be only the tension of the springs 28 and 29 upon the doors in their final closing movement 15 and which in practice, is for a distance between six or eight inches. However, the parts may be so adjusted to cause the springs 28 and 29 to function anywhere between the last four to eight inches of closing movement thus minimizing the danger 20 of injuring man, child or dog.

By having the drum 8 and the cylinder 23 mounted upon a common supporting member, 16 these portions of the mechanism 25 can be supplied in proper assembly and ready to be mounted at a desired location and which can be at any place preferred other than directly upon either of the doors D.

Secured to the outer end portion of the axle 14 and held thereto by a set screw 31 or the like is an upstanding arm 32 the upper end portion of which carrying a roller 33 contacting with the rack 19 from above 33 and thereby providing a retaining means for not only holding the drum 8 and gear 11 on the axle 14 but also maintaining the rack 19 in mesh with the gear 11.

In case anything should go wrong with 40 the air lines, the piston or more particularly the packing therefor should become worn and leaky or either the rod 21 or rack 19 become bent or broken or any part of such mechanism be temporarily put out of commission 45 the emergency can be readily met by the use of the crank 34. In applying the crank 34, the rack 19 is first disconnected from the rod 21 and removed as is also the arm 32. The crank 34 is then engaged with 50 the outer end portion of the axle 14 and secured to the gear 11 by the screws 35 preferably arranged at opposite sides of the opening 36 in the crank through which the outer end portion of the axle 14 is disposed. 55 After the crank 34 has been thus applied a collar 37 is slipped on the axle 14 outwardly of the crank 34 and held in desired position by the binding screw 38. With the crank 34 applied the doors D may be readily moved into open or closed position by manual operations and which can be employed until the necessary repairs have been made.

In the embodiment of our invention as 60 illustrated in Figures 9 to 12, we disclose an embodiment for use in connection with slid-

ing doors D'. The meeting edges of these doors at the upper portion thereof have secured to their inner faces the outstanding brackets 39, each of said brackets being offset with respect to the door D' to which it 70 is attached sufficient to clear the associated door when in closed position and also to permit the outer end portion of said arm or bracket 39 to be connected to a stretch of an endless cable 6'. This cable 6' passes around 75 the single sheave 40 at one side of the door opening 5' and engages the double sheave 41 at the opposite side of said door opening, said sheaves being supported by the door casing 42 and rotating about vertically disposed axes. The requisite pull upon the endless cable 6' is accomplished in the same manner as has been recited in connection with the first embodiment of our invention as herein set forth and the stretches of this 80 cable 6' also have associated therewith a shock absorbing medium similar to that hereinbefore described.

The arms or brackets 39 extending as they do beyond the meeting edges of the doors assure 85 said doors being moved into full open position.

The bolt 26 is particularly adapted for use when our improved mechanism is employed in connection with sliding doors as hereinbefore referred to and the desired adjustment of said bolt 26 may be maintained in a well-known manner through the medium of a locking nut 43.

While our improved mechanism may be 90 employed with advantage in connection with garages or other relatively heavy doors it is particularly adapted for use in connection with the doors of a grain elevator and 95 wherein it is required that the operating mechanism for such doors be contained within the elevator and associated with the inner sides of the doors. Further such mechanisms to be used in connection with grain elevators must be of a character where 100 no cables or chains will obstruct the driveway to prevent free passage of a vehicle during its entrance or exit. Furthermore in connection with grain elevators it is required 105 when swinging doors are employed that they move outwardly into open position. Our invention as herein disclosed fully meets all 110 necessary requirements.

From the foregoing description it is 115 thought to be obvious that a closure operating mechanism constructed in accordance with our invention is particularly well adapted for use by reason of the convenience and facility with which it may be assembled and operated, and it will also be 120 obvious that our invention is susceptible of some change and modification without departing from the principles and spirit thereof and for this reason we do not wish to be 125 understood as limiting ourselves to the pre-

cise arrangement and formation of the several parts herein shown in carrying out our invention in practice except as hereinafter claimed.

5. We claim:—

1. In combination with a closure member supported for movement into open or closed position, means for moving said door toward either of said positions, said means becoming inactive before the door is completely closed or opened, and automatic means for completing the opening or closing movement of the door.

10. In combination with a closure member movable into open or closed position, means for moving said member toward closed position, said means becoming inactive before the door is completely closed, and automatic means for completing the closing movement 20 of the door.

15. In combination with a closure member movable into either open or closed position, a flexible member operatively engaged with the door, means for imposing pull on said 25 flexible member to move said door toward closed position, said means becoming inactive before the door is completely closed, and means coacting with the flexible member for completing the closing movement of 30 the door.

30. In combination with a closure member

movable into either open or closed position, a drum, a flexible member adapted to wind around the drum, said member being operatively engaged with the door to move the 35 door into either open or closed position upon requisite rotation of the drum, means for rotating the drum, said flexible member being endless, the means for rotating the drum becoming inoperative before the door is completely closed, and means for imposing tension 40 upon each of the stretches of the flexible member operating to complete the closing movement of the door.

45. In combination with a closure member movable into either open or closed position, a drum, a flexible member adapted to wind around the drum, said member being operatively engaged with the door to move the door into either open or closed position 50 upon requisite rotation of the drum, means for rotating the drum, said flexible member being endless, the means for rotating the drum becoming inoperative before the door is completely closed, and retractile members 55 engaged with each of the stretches of the flexible member operating to complete the closing movement of the door.

In testimony whereof we hereunto affix our signatures.

HARRY G. KNAPP.

WILLIAM G. HANCOCK.
